UNITED STATES PATENT OFFICE

2,146,577

ELECTRIC DISCONNECT DEVICE

Benjamin R. Hermann, Lanesborough, Mass., assignor to General Electric Company, a corporation of New York

Application May 4, 1938, Serial No. 205,938

11 Claims. (Cl. 200—49)

The present invention relates to electric disconnect devices and more particularly to improvements in blade means for use therein.

One of the principal objects of the invention is the provision, in a disconnect device of the enclosed type, of improved blade means readily removable from the circuit which it is arranged to close and adapted to be left for long periods of time in an open circuit condition, wherein the conducting portion of the blade means is completely isolated from its co-operating contacts, without danger of current leakage due to accumulations of sleet, snow, and the like, and which blade means is arranged to give a clearly observable indication when in open circuit condition.

Another object of the invention is the provision of an improved cover or door for a housing of an electric cutout or the like adapted for outdoor installation, which cover or door while being of very simple and economical construction, is easily convertible to serve either as a simple closure device for the housing or as the blade means of an electric switch.

Other objects and the details of that which I believe to be novel and my invention will become apparent from the following description and the claims appended thereto, taken in conjunction with the accompanying drawing in which, for purposes of example, I have illustrated my invention as applied to the housing for an electric cutout of the type disclosed in my United States Patent No. 2,081,814, issued May 25, 1937, and assigned to the assignee of the present invention. It will be evident, however, from the ensuing description, that my invention is not limited to employment only in electric disconnect devices having cutout housings of the particular type illustrated.

In the drawing, Fig. 1 is a sectional elevation of the exemplary cutout housing with one form of blade means therefor embodying the present invention and with the electric connection means of the blade means in a closed circuit position; Fig. 2 shows, partially in sectional elevation, the device of Fig. 1 with the electric connection means in an open circuit and indicating position; and Fig. 3 shows, partially in sectional elevation, the cutout housing with a modified form of blade means embodying the present invention. Referring to the drawing, 10 designates an open front electric cutout casing which is constructed of porcelain or other suitable insulating material, and which has an integrally formed electric creepage barrier 11 disposed between stationary terminal contacts 12 and 13 carried by

the casing and adapted to have line conductors or leads fastened thereto. Upper contact 12 has a contact finger 14, backed by a spring strip 15, and formed to provide a latching seat 16 for a purpose to be described hereinafter. To the rear of the casing is secured a mounting bar 17, partially shown in the drawing, for attachment of the casing to an electric line pole and cross-arm structure or other supporting means. A pair of brackets 18, one of which is shown in the drawing and each of which has a hinge pin 19, are secured to the inner face of the rear wall of the casing adjacent the bottom thereof.

For closing the open front of casing 10, there is provided a cover or door 20 constructed of suitable insulating material and having the customary eyelet handle 21 for manual operation thereof. A somewhat U-shaped mounting member 22 is secured to the inner lower face of the door, and the substantially parallel extending spaced apart legs 23, one of which is shown in the drawing, of member 22, are provided with slots 24 suitably formed for engagement respectively with hinge pins 19 to pivotally support the door. On the inner face of the door and adjacent the top thereof is mounted a terminal element 25, by means of screws 26, which has a contact head 27 suitably shaped for engagement with the latching seat 16 of contact finger 14 to releasably hold the door in closed position.

As illustrated in Fig. 1, a conductor in the form of a flexible braid or cable 30, is supported by the door in position to effect electric connection between stationary contacts 12 and 13 of housing 10. The upper end of this conductor is provided with a terminal 31 having a slot 32 for readily releasable engagement with a wing screw 33 which is employable to effect clamping engagement of the conductor terminal with terminal element 25 carried by the door. The conductor is provided also with a readily removable bolt and nut assembly 34, located adjacent terminal 31, for a purpose pointed out hereinafter. The conductor is led downwardly between arms 23 of mounting member 22, almost to the bottom of the casing, and then is looped upwardly and provided with a contact terminal 35 arranged for co-operating engagement with the surface of lower stationary contact 13. This terminal 35 is pivotally mounted, as indicated at 36, on the upper end of an arm 37 which in turn is pivotally supported on a pin 38 extending between arms 23. Arm 37 is biased, by means of a spring 40, to effect pressure engagement of terminal 35 with contact 13 and the arrangement is such that, 35

upon closing of door 20, the surface of terminal 35 slidably contacts the surface of contact 13 to clean these two surfaces and thereby insure a good electric connection. Door 20 may be rotated 5 manually, by means of handle 21, about hinge pins 19 and, with conductor 30 supported as illustrated in Fig. 1, may be operated as a disconnect blade or may be left in closed position to complete the electric connection between contacts 12 and 13. When in closed position, the door 10 effectively protects the internal parts of the housing from adverse weather conditions.

When it is desired to employ door 20 simply as a closure for the open front of casing 10, it is necessary only to detach upper conductor terminal 31 from upper door supported terminal element 25 and then to pull the flexible conductor to its position illustrated in Fig. 2. Arm 37 is provided with a hook projection 41 so that, under 15 this last condition, the arm may be latched back against the door by means of a ring 42 which is held in place by an upwardly projecting portion 43 of member 22, as shown in Fig. 2. Thus both ends of conductor 30 are completely isolated from 20 stationary contacts 12 and 13. The upper terminal 31 of the conductor may be held in its lowered position in any suitable manner, as for example, by engagement of bolt and nut assembly 34 with a stop 44 at the lower end of member 22 and engagement of the end of spring 40 with the slot 32 25 in terminal 31. Removal of the bolt and nut assembly and withdrawal of the end of spring 40 from slot 32 may be accomplished readily when it is desired to service or replace the conductor. 30 When terminal 31 is in its lowered position shown in Fig. 2, a looped portion of the flexible conductor extends below the bottom of the casing to give clearly visible indication of the open circuit condition. At the same time, the door remains in closed position to protect the internal 35 parts of the housing from adverse weather conditions. If it is desired for any reason to open the door and swing it downwardly about hinge pins 19, conductor 30, being flexible, provides no 40 hindrance to such movement as would be the case if the conductor were in the form of a stiff 45 rodlike element.

In the modification of Fig. 3, the door is hinged supported on pins 19 by means of a U-shaped mounting member 45 somewhat similar to mounting member 22 of the previously described embodiment. The conductor 46 in this modification is made in the form of one or more flexible strips and is provided with an upper terminal 47 having a contact head 48 arranged 50 to be detachably supported on a bracket 50 carried by the door. Contact head 48 engages upper stationary contact finger 14, and the door is held releasably in closed position by engagement of 55 the seat portion 16 of contact finger 14 with the head 48 and, in the illustrated embodiment, also with upwardly extending projections 51 of bracket 50. However, engagement of seat 16 with projections 51 is not necessarily required when the 60 conductor is in connected position. The lower end of conductor 46 has a contact terminal 52 pivotally connected, as indicated at 53, to an arm 54 which in turn is pivotally supported on a pin 55 which extends between the spaced arms 65 of mounting member 45. Arm 54 is biased by means of a spring 56 for counterclockwise rotation, as viewed in Fig. 3, so as to force lower conductor terminal 52 into pressure engagement 70 with contact 13, the arrangement being such, 75 similar to that of the previously described em-

bodiment, that a sliding engagement of terminal 52 with contact 13 is effected as door 20 is moved to closed position.

When it is desired to employ the door simply as a closure for the open front of casing 10 without establishing electric connection between lower stationary contact 13 and contact finger 14 of the upper stationary contact of the housing, the door is pulled open and mounting member 45 is disengaged from hinge pins 19. Disengagement 10 of contact head 48 from bracket 50 then permits arm 54 to rotate in a counterclockwise direction, under the influence of spring 56, so that the arm may assume its position illustrated in broken lines in Fig. 3. Contact head 48 then may be 15 brought around and latched between the curved end of arm 54 and the inner surface of member 45, as shown in broken lines in Fig. 3, or may be allowed to hang down freely. The door then is returned to engagement with hinge pins 19 and 20 is rotated to its closed position where it is latched by engagement of projections 51 with seat 16. Under these circumstances flexible conductor 46 hangs downwardly below the bottom of the casing so as to give clear indication of the open circuit 25 condition, while the door is maintained in position to protect the internal parts of the housing from adverse weather conditions. Conductor 46, being flexible, does not effect any hindrance to 30 swinging of the door to open position when desired.

As will be evident from the foregoing description, the present invention provides pronounced advantages over suggestions heretofore made for replacement doors for electric cutout housings. 35 It has been suggested to provide such a door with a conducting element or blade of stiff construction fastened rigidly to the door in position to bridge the stationary contacts of the cutout housing. In such case, if no provision were made 40 for ready removal of the blade from the door, it would be necessary to remove the door as well as the blade from the housing when it is desired to leave the circuit open. This would be a great disadvantage in that either the housing would be 45 left open with the possibility of sleet and snow collecting on the internal parts and causing current leakage across the contacts, or a lineman would be put to the inconvenience of carrying a large number of separate doors for replacement 50 purposes at those installations where it is desired to convert from closed to open circuit condition, or vice versa. In case provision were made for removal of the blade from the door when it is desired to leave the circuit open, the disadvantage 55 would be encountered that the lineman would have no ready means for observing, when the door is closed, whether or not the blade is in position to close the circuit.

The present invention effectively and simply 60 avoids the disadvantages of the earlier suggestions above mentioned, in that it makes possible the provision, at the cutout housing installation, of a single cover or door having all parts necessary for quick and easy conversion of the cover 65 or door to serve either as a simple housing closure or as a circuit closing blade means. Thus, there is no danger of a lineman having to leave a cutout housing open for long periods of time to 70 adverse weather conditions merely because he does not happen to have a separate bladeless cover available when he desires to convert the installation from closed circuit condition to open circuit condition. Also, with the construction 75 of the present invention, the lineman is not put 75

to the inconvenience of climbing a pole or other supporting structure and removing the cutout housing cover to determine the condition of the installation, since the clearly observable presence or absence of the downward hanging conductor readily indicates whether the circuit is open or closed. However, with the described construction the conductor, when in downward hanging indicating position, does not in any way hinder manual operation of the door. In addition to the advantages pointed out above, devices embodying the present invention have the further important advantage of extremely economical and simple construction which requires no adjustment or

15 inconvenient service operations in the field.

As will be evident from the foregoing description, my invention is not limited to the particular details of construction of the exemplary embodiments illustrated, and I contemplate that various other modifications and applications of the invention will suggest themselves to one skilled in the art. It is my intention therefore that the appended claims shall cover such other modifications and applications as do not depart 25 from the true spirit and scope of the present invention.

What I claim as new and desire to secure by Letters Patent of the United States, is:

1. In an electric disconnect device, the combination of a housing comprising a casing and a door for closing an open side of the casing, spaced contacts in said housing, a conductor having a flexible section, means employable for supporting said conductor in said housing in a position electrically connected between said contacts, and means employable for supporting the conductor alternatively in a position electrically isolated from at least one of said contacts with said flexible portion depending in a loop from an opening 40 at the bottom of said housing to indicate the isolated condition of the conductor.

2. In an electric disconnect device, a casing, spaced contacts therein, a flexible conductor, and a door mounted for removably closing an open side of said casing and having means employable for supporting said flexible conductor electrically connected between said contacts, said door having means employable when the door is closed for supporting the conductor alternatively in a position electrically isolated from at least one of said contacts and with a portion of the conductor depending flexibly from an opening at the bottom of said casing in a manner to give indication of the isolated condition of the conductor.

3. In an electric disconnect device, a casing, spaced upper and lower contacts therein, a switch element, a door pivotally mounted adjacent its lower end and arranged to close an open side of said casing, said door having means employable for supporting said switch element electrically connected between said contacts, and means associated with the door employable for supporting said switch element alternatively in another position electrically isolated from at least one of said contacts, said switch element having a part arranged to depend flexibly substantially below the bottom of said casing when the switch element is in its said other position, thereby to indicate the isolated condition of the switch element without hindrance to movement of said door about its pivotal mounting.

4. Electric disconnect blade means for use with a supporting casing having an open side and spaced contacts mounted therein; said blade means comprising a switch element having a flex-

ible section, a door adapted for mounting in closing relation to an open side of a supporting casing and having spaced supports arranged to support said switch element in position for electric connection between spaced stationary contacts of a supporting casing, means for detachably connecting said switch element to one of said supports, and means associated with said door employable, when the door is mounted in closing relation to the open side of a supporting casing and said switch element is detached from said one support, for supporting the switch element in an electrically disconnected position with a portion of the switch element depending flexibly in an indicating position below the bottom 15 of the door.

5. Electric disconnect blade means for use with a supporting casing having an open side and spaced contacts mounted therein; said blade means comprising a flexible conductor, a door 20 adapted for mounting in closing relation to an open side of a supporting casing, said door having spaced supports arranged to support the ends of said conductor in electrically conductive relation respectively with spaced stationary contacts 25 of a supporting casing, means for connecting one end of the conductor to one of said supports, means for detachably connecting the other end of the conductor to the other of said supports, and means associated with said door employable, 30 when the door is mounted in a closing position and said other end of the conductor is detached from said other support, for supporting the ends of the conductor in electrically isolated positions with a portion of the conductor depending in a 35 loop below the bottom of the door.

6. Electric disconnect blade means for use with a supporting casing having an open side and spaced upper and lower stationary contacts mounted therein; said blade means comprising a 40 flexible conductor, a door adapted to be mounted in closing relation to an open side of a supporting casing and having spaced contact terminals arranged for engagement respectively with spaced stationary contacts of the supporting casing, 45 means for connecting one end of said conductor to one of said terminals and means for detachably connecting the other end of the conductor to the other of said terminals, a portion of said conductor being arranged to depend in an indicating position from the bottom of said door upon detachment of said other end of the conductor from said other terminal.

7. Electric disconnect blade means for use with a supporting casing having an open side and 55 spaced upper and lower stationary contacts mounted therein; said blade means comprising a flexible conductor, a door adapted to be mounted in closing relation to an open side of a supporting casing and having means arranged for supporting one end of said conductor in a position for electric connection with one of a pair of spaced stationary contacts of the supporting casing, a contact terminal secured to the other end of said conductor, and a bracket carried by the door 60 arranged for detachably supporting said contact terminal in engagement with the other of such pair of contacts, a portion of said conductor being arranged to depend in an indicating position from the bottom of said door upon detachment 65 of said terminal from said bracket.

8. Electric disconnect blade means for use with a supporting casing having an open side and spaced stationary contacts mounted therein; said blade means comprising a flexible conductor, a 75

- door adapted to be mounted in closing relation to an open side of a supporting casing and having means employable for effecting electric connection of said conductor between spaced stationary contacts of a supporting casing, said last mentioned means including a contact terminal for engagement with a corresponding stationary contact, means supporting said terminal for movement relative to said door, means operable for effecting pressure engagement of said terminal with a corresponding stationary contact when the door is mounted in a casing closing position, and means employable for restraining said terminal alternatively in a position electrically isolated from such corresponding stationary contact when the door is mounted in a casing closing position.
9. In combination, a door adapted for mounting in closing relation to an open side of a supporting casing, means associated with the door arranged to support an electric conductor for connection between spaced stationary contacts mounted in a supporting casing, a contact terminal for engagement with a stationary contact, pivoted means associated with said door and supporting said terminal for movement relative to the door, means operable for effecting pressure engagement of said terminal with a corresponding stationary contact when the door is mounted in a casing closing position, and means employable for restraining said terminal alternatively in a position electrically isolated from such corresponding stationary contact when the door is mounted in a casing closing position.
10. In combination, a door adapted for mounting in closing relation to an open side of a supporting casing, means associated with the door arranged to support an electric conductor for connection between spaced stationary contacts mounted in a supporting casing, a contact terminal for engagement with a stationary contact, pivoted means associated with said door and supporting said terminal for movement relative to the door, means operable for effecting pressure engagement of said terminal with a corresponding stationary contact when the door is mounted in a casing closing position, and means employable for restraining said terminal alternatively in a position electrically isolated from such corresponding stationary contact when the door is mounted in a casing closing position.
11. In combination, a door adapted for mounting in closing relation to an open side of a supporting casing, means associated with the door arranged to support an electric conductor for connection between spaced stationary contacts mounted in a supporting casing, a contact terminal for engagement with a stationary contact, pivoted means associated with said door and supporting said terminal for movement relative to the door, means operable for effecting pressure engagement of said terminal with a corresponding stationary contact when the door is mounted in a casing closing position, and means employable for restraining said terminal alternatively in a position electrically isolated from such corresponding stationary contact when the door is mounted in a casing closing position.

mounted in a supporting casing, a contact terminal for engagement with a stationary contact, a pivoted terminal support associated with said door and movable relative to the door, means pivotally mounting said terminal on said terminal support, and means operable when said door is mounted in a casing closing position for effecting pressure engagement of said terminal with a corresponding stationary contact.

11. Unitary replaceable blade means for use in an electric disconnect device including a supporting casing having an open side and stationary upper and lower contacts mounted therein; said blade means comprising a door adapted for removable mounting in closing relation to an open side of a supporting casing, a flexible conductor, means arranged detachably to support one end of the conductor in a position for electric connection with an upper casing contact, means employable for supporting said one end of the conductor alternatively in another position electrically isolated from such upper casing contact when the door is mounted in a casing closing position, a contact terminal for the other end of the conductor, pivoted means supporting said terminal for movement relative to the door into and out of engagement with a lower casing contact, biasing means operable for effecting pressure engagement of said terminal with such lower casing contact, and means employable for restraining said terminal alternatively in a position electrically isolated from such lower casing contact when the door is mounted in a casing closing position, a portion of said conductor being arranged to depend in a loop at the bottom of said door when said one end of the conductor is supported in its said other position.

BENJAMIN R. HERMANN.
